UNITED STATES PATENT OFFICE.

JAMES F. BURNS, OF PHILADELPHIA, PENNSYLVANIA.

CAN-FILLER.

SPECIFICATION forming part of Letters Patent No. 633,792, dated September 26, 1899.

Application filed March 1, 1898. Serial No. 672,215. (No model.)

To all whom it may concern:

Be it known that I, JAMES F. BURNS, of Philadelphia, in the State of Pennsylvania, have invented certain new and useful Improvements in Can-Fillers, whereof the following is a specification, reference being had to the accompanying drawings.

My invention relates particularly to that class of can-filers in which the opening of the filler-valve is not dependent upon the insertion of the filler in the can, but is effected by the manipulation of an external handle.

Generally stated, my invention comprehends a nozzle-pipe provided with a valve and a float arranged in such relation with said valve as to close the latter after the influx of a predetermined quantity of water to the can in which the apparatus is inserted.

In the accompanying drawings, Figure 1 is a central vertical section through the can, showing a convenient embodiment of my invention applied thereto. Fig. 2 is a plan view of the parts shown in Fig. 1. Fig. 3 is a fragmentary sectional view showing a modified form of my invention. Fig. 4 is a sectional detail view taken on the line 4-4 of Fig. 1.

In said figures, A is the can, and B the nozzle-pipe of the filler.

30 B' is the head of the pipe B, provided with the elbow b' for convenient connection to a flexible pipe leading from the water-supply. B² is a skeleton frame fixed upon said pipe B, whereby the latter is upheld in proper position with respect to the can. Said frame is fixed at its upper extremity upon the head B', as indicated at b², and at its lower extremity upon the collar b³, fixed upon the pipe B.

40 The valve-casing C is fixed upon the lower extremity of the pipe B. The valve C' is mounted in said casing and provided with the packing-washer C², adapted for watertight contact with the valve-seat c². The 45 valve-stem C³ is bifurcated at its lower extremity c³ to embrace the lever C⁴. Said lever C⁴ has a cup-shaped outer extremity to receive the valve-rod D.

The valve-rod D is mounted for vertical re-50 ciprocation in the pipe-head B' and conven-

iently provided at its upper extremity with an operating handle or knob D'.

The pressure of water within the pipe B serves to normally maintain the valve C' upon the seat c², and said valve is manually 55 opened by vertical downward movement of the rod D after the filler is in fixed relation with the can. The relation of the parts is such that when said valve C' is manually lifted from its seat, as aforesaid, the weight of 60 the rod D, together with the reflex action of the water flowing from the valve-chamber C⁵, serves to maintain the valve C' in open position until the latter is relieved of the weight of the rod D, whereupon the pressure 65 of the water within the pipe B serves to close said valve upon its seat c².

In the form of my invention shown in Fig. 1 the float E normally rests upon the collar F, which is adjustably secured upon the pipe B by the set-screw f, and the collar D² is adjustably secured upon the valve-rod D by means of the set-screw d². The relation of the float E and the collars F and D² is such that the water rising within the can A to a level pre-70 determined by the adjustment of the collar D² lifts said float E into contact with said collar D², and thereby raises the valve-rod D and permits the valve C' to close under the pressure of the water in the pipe B. 75

In the form shown in Fig. 3 the float E normally rests upon the collar D³, which is adjustably secured upon the rod D by means of the set-screw d³. The weight of the float E is therefore added to that of the rod D, &c., 80 to maintain the valve C' in open position against the water-pressure in the pipe B until the rising water lifts said float into contact with the collar D², as aforesaid. 85

I am aware that it is not broadly new to operate a can-filler valve by means of a slideable float, and I therefore do not desire to broadly claim such construction. I believe it to be broadly new, however, in can-filers of the particular type which I have described 90 to provide a float which permits the closure of the valve in the manner herein set forth when a predetermined water-level is reached. 95

It is obvious that various modifications may be made without departing from the spirit of 100

my invention. I therefore do not desire to limit myself to the precise construction which I have shown and described.

I claim—

- 5 In a can-filler, the combination with a portable nozzle-pipe provided with a bearing-lug, of a valve at the extremity of said pipe adapted to be closed by the water-pressure therein, a float mounted upon said nozzle-pipe in slidable relation therewith, a valve-rod exterior to said pipe, connected with said float and extending above said float through said bearing-lug, and a lever pivoted in the

lower extremity of said pipe, connected to said rod and adapted to contact with said valve, said parts being arranged so that said valve-rod may be manually operated above said float to open but not to close said valve, and automatically operated by said float to permit the closing of said valve, substantially as set forth.

JAMES F. BURNS.
